Primary Examiner — Samantha Wood

(57) **CLAIM**

The ornamental design for a movement for clock and watch as shown and described.

DESCRIPTION

1.1 is a front view of a movement for clock and watch;
1.2 is a perspective view of the rear, bottom, and left side thereof;

1.3 is a rear view thereof;

1.4 is a right side view thereof;

1.5 is a left side view thereof;

1.6 is a bottom view thereof;

1.7 is a top view thereof;

1.8 is a perspective view of the front, bottom, and right side thereof;

1.9 is a perspective view of the front, bottom, and left side thereof; and

1.10 is a perspective view of the rear, bottom, and right side thereof.

(Continued)

The portions of the movement for clock and watch shown in broken lines form no part of the claimed design.

1 Claim, 10 Drawing Sheets
